SIGNAL CLEARING RELAY FOR CENTRALIZED TRAFFIC CONTROL SYSTEMS OF THE CODE TYPE

James I. Grammer, Western Springs, Ill., assignor to Westinghouse Air Brake Company, a corporation of Pennsylvania

Application February 19, 1946, Serial No. 648,716

3 Claims. (Cl. 246—3)

1

My invention relates to centralized traffic control systems for railroads, and to improved apparatus for the remote control of railway signals or the like, by a selective communication system of the code type, such for example, as that shown in Letters Patent of the United States, No. 2,229,249, issued January 21, 1941, to Lloyd V. Lewis, for Remote Control Systems.

In remote control systems of this type, the components are assembled in the form of individual storage units with each identified by a selective code call and adapted to control and indicate a related group of traffic governing devices, such as a track switch, and the railway signals which govern traffic movements over the switch. Each unit is linked, by means of its code call, with a corresponding storage unit located in the office control machine which governs the transmission of a code including its code call followed by a series of code elements for controlling the switches and signals in accordance with the positions of their control levers, when set into operation by pressing a code starting button to select the code call. Each office storage unit also includes a group of indication stick relays which respond to the elements of indication codes transmitted from the associated station unit to indicate the condition of the switch and signals and for also indicating the condition of one or more track sections.

The present invention relates more particularly to the control of railway signals by systems of this character, and provides novel and improved means for preventing a change in the character of a code element for controlling a signal to its clear or stop position, except by the combined operation of the signal lever and of a code starting button associated with but independent of the lever, or upon the reception of a code indicating that a train has accepted a signal and has caused it to be put to stop.

Briefly described, my invention is embodied in a signal clearing relay for electrically interlocking each signal lever with the associated code starting button, and with a code-controlled indication relay of the system which is operated whenever the corresponding signal is put to stop by a passing train. The contacts of the signal clearing relay replace the usual lever contacts in the circuits for effecting the code control of the signal, and this relay is arranged to be picked up, when the signal lever has been placed in its reverse or signal clearing position, only by operating the associated code starting button and then only if the indication relay referred to re-

5 flects the proper track conditions. The signal clearing relay may be released by the operator to effect the manual control of the signal to stop, only by operating the starting button after he has restored the signal to its normal position. This relay is released automatically, by the operation of the indication relay referred to, when the signal is put to stop by a passing train. Applicant's signal lever and code starting button 10 are thus interlocked so as to require their combined operation to change the character of a signal controlling code element, without any mechanical connection, with the advantage that the operator is enabled to operate the lever between its normal and reverse positions without causing the transmission of a control code whenever this is desirable.

One object of my invention is to facilitate the control of unrelated devices by the same storage 20 unit, so that a code containing an element assigned to the control of a signal or the like may also include elements for controlling other devices having starting buttons for actuating the same storage unit, and when codes are initiated by the 25 operation of starting buttons associated with such other devices, the element which controls the signal will retain the same character as originally established, even though the position of the signal lever has inadvertently changed, so long as the starting button directly associated with the 30 signal lever is not operated. My invention is particularly advantageous in connection with the control of two or more unassociated signals by the same storage unit, and also in connection 35 with the control of single track signaling systems of the reversible type, in which the operation of the starting button for the signal at either end of a block is effective, at times, to cause the transmission of codes to both ends of the block in order to reverse the direction of traffic movement, as shown, for example, in an application for Letters Patent of the United States, Serial No. 501,254, filed September 4, 1943, by Henry S. Young, for Railway Traffic Controlling Apparatus, now Patent No. 2,420,579, issued May 13, 1947.

My invention is an improvement on that shown and claimed in application for Letters Patent of the United States, Serial No. 649,598, of Arthur L. Jerome, Lloyd V. Lewis and Frank T. Pascoe, filed February 23, 1946.

Other objects and features of my invention will be pointed out as the description proceeds.

I shall now describe one form of apparatus

embodying my invention and shall then point out the novel features thereof in claims.

Referring to the accompanying drawing, in order to illustrate my invention in a relatively simple manner, I have shown it applied to the control of two railway signals 2R and 4L, as shown in the track plan at the right of the drawing, which signals are independently controllable by their respective signal levers 2SG and 4SG. In such cases it is preferable to mount the levers in separate panels or sections of the operator's control board to more readily identify the levers with the signals on the track diagram mounted above the levers.

It is to be understood that the signals are controlled and indicated by a code type communication system such as that shown and described in the hereinbefore mentioned Lewis patent, employing but one office storage unit and one station storage unit of the system. The general mode of operation of this system is well known and a detailed explanation thereof is not needed for an understanding of my invention, and the portions thereof relating directly to my invention are illustrated herein in a simplified diagrammatic form. To further simplify the circuits, only the terminals of the local sources of current for energizing the relays are shown, these being identified by the reference characters B and C, respectively.

Each signal lever 2SG or 4SG has a starting button 2STB or 4STB, which is effective when operated to energize the office starting relay OST over contact *a* of the button to initiate the transmission of a code containing a distinctive code call by which a selector relay OS at the office and a delivery relay D are operated to link the office unit with the corresponding station unit. Each signal lever has a signal clearing relay 2RGS or 4LGS associated therewith in accordance with my invention. Each relay 2RGS or 4LGS picks up over the lever contact *a* and the normally open starting button contact *b* when the associated starting button 2STB or 4STB is operated, provided the controlling signal lever is then in its reversed or signal clearing position, and is held energized after the button is released by a stick circuit including its contact *a* and the normally closed contact *b* of the button after the latter is released, regardless of the lever position. Each relay 2RGS or 4LGS may be released manually by pressing the associated starting button when the lever is in its normal position, as shown, and is also released automatically when a code is received indicating that a train has accepted the signal and put it to stop by entering the controlling track section 1T or 3T.

When a control code is transmitted, a series of control channels are momentarily established, of which but three are shown, designated 1, 3 and 4 and represented simply as direct wire connections as may also be used when the signals are but a short distance from the office, whereby the signal control relays 2RHS and 4LHS and a maintainer's call relay US are operated to positions corresponding to those of relays 2RGS and 4LGS and of a maintainer's call key MC. Relay US serves to control a call signal lamp E for calling the maintainer to the telephone provided in systems of this character, while relays 2RHS and 4LHS and the track relays 1TR and 3TR control the mechanisms 2RG and 4LG for the signals 2R and 4L, as shown.

The delivery relay D also has a contact *j* for energizing the station starting relay ST to initiate

the transmission of a return indication code following the reception of each control code. In the code initiated by relay ST, a start release relay VC is operated to release relay ST, also a connector relay MSP at the station and a delivery relay OD at the office are operated to establish four indication channels 9 to 12, whereby the track indication relays 1TK and 3TK are picked up, if the track sections 1T and 3T are occupied, to light red lamps 1TKE and 3TKE on the track diagram, and to release relay 2RGS or 4LGS, if energized. If signal 2R or 4L is at clear, a signal indication relay 2RHK or 4LHK is picked up over channel 10 or 12, respectively, to light a green lamp 2RE or 4LE mounted above the corresponding lever, and to extinguish the red lamp 2NE or 4NE associated therewith.

Channel 9 is controlled by the track storage relay 9TS, which is energized over back contact *c* of the track relay 1TR, and serves to prevent the loss of a track occupied indication in the event its transmission is delayed until the section is vacated. Relay 9TS is provided with a stick circuit controlled by a valve relay 9V associated therewith, which functions like the similarly designated relay of the Lewis patent, and it is to be understood that relay 9V picks up when a track occupied code is fully transmitted over the corresponding channel, and releases when a track clear code is fully transmitted over that channel. Contacts *c* of relays 9V and 9TS provide circuits for energizing relay ST to initiate the transmission of a code in response to a change in the position of relay 9TS.

It will be seen that if the track relay 1TR releases to pick up relay 9TS, relay ST will pick up over front contact *c* of relay 9TS to initiate the transmission of a code in which channel 9 is energized over back contact *c* of the track relay 1TR to indicate the occupancy of section 1T. If it happens that relay 1TR picks up before the track occupied code is transmitted, terminal B at back contact *a* of relay 9V will hold relay 9TS energized and will apply energy to channel 9 until the track occupied code by which relay 9V is picked up is transmitted.

Channel 11 is similarly controlled by relay 3TR, but this channel is also employed to transmit an additional indication controlled by a power-off relay POR for which it may be assumed that a separate channel is unavailable.

It is to be understood that the source of current at the station having the terminals B and C is a battery which is normally maintained charged by a primary source of power having the terminals BX and CX across which relay POR is connected. In the event of failure of the primary power, relay POR releases to complete a circuit from terminal B at back contact *a* of relay US over back contact *b* of relay POR and back contact *a* of relay 3TX to energize relay 11TS and channel 11, and relay ST is picked up over a circuit closed momentarily over back contact *a* of relay POR and front contact *a* of a repeating relay POR to transmit a code to pick up relay 3TK and to thereby light lamp 3TKE. If lamp 3TKE becomes lighted when signal 4L has not been cleared, or if it becomes lighted when the signal has been cleared and lamp 4LE remains lighted, the operator reverses the maintainer's call key MC, and transmits a code to pick up relay US, which lights lamp E and disconnects terminal B from back contact *b* of relay POR to cancel the indication displayed by lamp 3TKE. The power-off indication is thus distinguishable

from the track- occupied indication transmitted over the same channel, due to track occupancy or track circuit failure, by the fact that the operator is enabled to cancel it at will.

I shall now assume that the apparatus is in its normal condition, and that the operator reverses lever 2SG and presses button 2STB, thereby energizing relays 2RGS and OST and initiating a control code by which relay 2RHS is energized over channel 1, this channel being supplied with energy over contact c of relay 2RGS. Mechanism 2RG becomes energized over contact c of relay 2RHS and contact a of relay 1TR to cause signal 2R to indicate clear, and the closing of contact j of relay D when the control code is received energizes relay ST to initiate a return indication code by which relay 2RHK is energized to light lamp 2RE and extinguish lamp 2NE, relay 1TK remaining released.

Other control codes may now be transmitted by the same unit, to clear signal 4L or operate relay US, in each of which the energy applied to channel 1 by contact c of relay 2RGS maintains relay 2RHS energized as required, even though lever 2SG is inadvertently moved to open its contact a.

I shall now assume that a train enters section 1T, releasing relay 1TR to restore signal 2RG to stop and energizing relays 9TS and ST to store an indication code for transmission, but that the transmission of this code is delayed, due perhaps to the transmission of indication codes having superior code calls over the same code line. As explained in the Lewis patent, control codes take precedence over indication codes, and codes for controlling signal 4L or lamp E may be transmitted under this condition, but the operator will be unaware of the occupancy of section 1T. Relay 2RHS is released by the opening of contact b of relay 1TR and is maintained released by the opening of back contact d of relay 9TS. It follows that relay 2RHS will not respond to a signal clearing code as long as relay 9TS is picked up even though section 1T has been vacated, and signal 2R will not be cleared by a code received prior to the transmission of the track occupied indication.

When the code stored by relay ST is being transmitted, relay 9TS is in its picked up position and mechanism 2RG is released, so that this code energizes relay 1TK to light lamp 1TKE and to release relay 2RGS, and also releases relay 2RHK to light lamp 2NE and extinguish lamp 2RE, and at the end of this code relay 9V picks up to open the circuit for relay ST extending to terminal B at front contact c of relay 9TS and also opens the stick circuit for relay 9TS, but if section 1T is still occupied, relay 9TS is held energized by relay 1TR, and holds relay 2RHS released. If section 1T has been vacated, relay 9TS is released by relay 9V, completing a new circuit for relay ST over back contact c of relay 9TS and front contact c of relay 9V, to initiate the transmission of an indication code to release relay 1TK and extinguish lamp 1TKE. Relay 9V is released by this code to open the circuit over which relay ST was energized. Back contact d of relay 9TS is now closed, rendering relay 2RHS responsive to control codes in which energy is applied to channel 1, but relay 2RGS has been released by the preceding indication code and channel 1 is now open. Consequently relay 2RHS will not become energized to reclear signal 2R, by control codes which include an element assigned to the control of relay 2RHS, even though

lever 2SG is moved to a position to close its contact a, unless button 2STB is also operated to pick up relay 2RGS.

Following a temporary interruption of the communication system, the operator may wish to send codes to the different stations for the purpose of causing indication codes to be transmitted, in order to obtain information concerning train movements and the condition of the signals before issuing new controls. Even though the code for governing signal 2R does not control other devices, the provision of the signal clearing relay 2RGS is of utility under this condition because if signal 2R stood at clear at the time the interruption occurred, it may be that it will have been put to stop by a train before the system is restored, but in any case, the transmission of a control code for clearing it, by operation of button 2STB with lever 2SG reversed, after the system is restored, will not change its condition. That is to say, if signal 2R is still at clear the code will maintain it clear, and if it has been put to stop by a train the circuit for relay 2RHS is held open by relay 9TS, due to the fact that an indication of the occupancy of section 1T has not been transmitted, rendering the code ineffective to reclear the signal.

The signal clearing relay 2RGS is also of utility wholly apart from the control by the track storage relay 9TS. In the control of single track signaling, for example, it is a common practice for an operator to reverse the lever for the entering and leaving signals for a block and to then press the starting button for the entering signal only, delaying the clearing of the leaving signal until he has determined whether or not the train should enter a siding at the location of the leaving signal. In certain systems, the operation of the entering end starting button is arranged to cause the transmission of codes to both ends of the block, as already mentioned, one of which would cause the leaving signal to clear under the conditions mentioned, in the absence of a signal clearing relay such as relay 2RGS for that signal. In the system referred to, and in fact, in signaling systems generally, the clearing of a signal controlling movements over a track switch renders time locking effective to prevent the operation of the switch. It follows that the inadvertent clearing of the leaving signal under the condition mentioned would delay the movement of the train into the siding, if this were required.

Although in the foregoing I have described my invention principally with reference to signal 2R, it is to be understood that the circuits for signal 4L are similar, except as modified to provide for indicating the power-off conditions by lamp 3TKE. These modifications include a front contact b of the signal indication relay 4LHK bridging contact b of relay 3TK, in the circuit for relay 4LGS, in order to prevent its release when relay 3TK is picked up by the release of relay POR. The energization of relay 4LHK along with relay 3TK obviously indicates that the track relay 3TR has not been released. Back contact c of the track relay 3TR controls a pick-up circuit for relay 11TS in which a repeating relay 3TX is interposed, so that relays 3TX and 11TS pick up in cascade in response to the release of relay 3TR. Relay 11TS is held energized by relay 11V and relay 3TX is held energized over a stick circuit controlled by relay 11TS. The reason for this arrangement is that a back contact of relay 11TS, corresponding to contact d

of relay 9TS in the circuit for relay 2RHS, cannot properly be included in the circuit for relay 2LHS, to prevent its energization by a control code received after section 3T is vacated but prior to the transmission of an indication code by which relay 11TS is released, since this might cause signal 2L to be put to stop improperly, as a result of the operation of relay POR. Accordingly, the repeating relay 3TX is provided, having a back contact *b* in the circuit for relay 2LHS in place of a contact of relay 11TS. Relay 3TX serves to hold the circuit for relay 4LHS open when relay 11TS is picked up by the release of relay 3TR, but not when relay 11TS is picked up by the release of relay POR, as will be readily apparent from the drawing.

Although I have herein shown only one form of apparatus embodying my invention and one modification thereof, it will be understood that various modifications may be made therein within the scope of the appended claims without departing from the spirit and scope of my invention.

Having thus described my invention, what I claim is:

1. In a centralized traffic control system, a control relay, a communication system for governing the operation of said relay from a control office; a control lever, a stick relay, and a starting button, all located at said office, means responsive to the operation of said starting button for causing the communication system to operate the control relay to a position determined by that of said stick relay, a pick-up circuit for the stick relay including a reverse contact of said lever and a normally open contact controlled by said button, and a stick circuit for the stick relay including said signal lever contact bridged by a normally closed contact controlled by said button.

2. In a centralized traffic control system having a communication system connecting an office and a station, a railway signal for controlling traffic movements over a detector track section, a track relay for said section, a signal control relay controlled over a front contact of said track relay, a second control relay and a locally controlled normally energized relay, all located at said station; a track indication relay which is energized by said communication system when the track relay is released and also when both said second control relay and said normally energized relay are released, a signal indication relay controlled by said communication system which reflects the condition of said signal control relay, a signal lever for governing the signal control relay, a second lever for governing the second control relay, and a stick relay all located at said office, pick-up and stick circuits for eff-

fecting the energization or release of said stick relay in accordance with the position to which said signal lever is operated, said circuits including a back contact of said track indication relay bridged by a contact closed by said signal indication relay if the signal control relay is energized, means governed by said communication system for energizing said signal control relay when said stick relay is energized and for controlling said second control relay in accordance with the position of said second lever, and means associated with said levers for visually indicating the positions of said indication relays.

3. In a centralized traffic control system, a detector track section having a track relay, a signal for governing traffic movements over said section, a control relay for the signal having a normal and a signal clearing position, a code type communication system for governing said control relay from a control office and for indicating the condition of occupancy of said detector track section at said office; a control lever, a stick relay and a starting button for causing the transmission of control codes by said communication system, all located at said office, a storage relay at the station controlled by said track relay for causing indications of the occupied or unoccupied condition of said detector section to the office and for storing each occupied indication until such indication is transmitted, pick-up and stick circuits for said stick relay including a contact closed only when said unoccupied condition is indicated, said pick-up circuit including a reverse contact of said lever and a normally open contact of said button, said stick circuit including said lever contact bridged by a normally closed contact of said button, means for operating said control relay to its signal clearing position in response to a control code transmitted when said stick relay is energized provided said storage relay has not been operated to store an indication code for transmission, and means for operating said control relay to its normal position in response to a control code transmitted when said stick relay is released.

JAMES I. GRAMMER.
